UNITED STATES PATENT OFFICE.

HARRY S. VINCENT, OF RIDGEWOOD, NEW JERSEY.

LOCOMOTIVE-FEED-WATER HEATER.

1,266,185.

Specification of Letters Patent.

Patented May 14, 1913.

Application filed July 23, 1917. Serial No. 132,613.

To all whom it may concern:

Be it known that I, HARRY S. VINCENT, of Ridgewood, in the county of Bergen and State of New Jersey, have invented a certain new and useful Improvement in Locomotive-Feed-Water Heaters, of which improvement the following is a specification.

My invention relates to locomotive feed water heaters of the "surface" type, in which the transference of heat from the heating agent, which may be either exhaust steam or waste gases, to the feed water, is effected through separating walls of metal. Either one or the other of the heating mediums noted has, heretofore, been ordinarily applied, and apparatus operating under their joint and serial application has also been put in practice to a limited extent. A substantial objection to the use of exhaust steam only, is, that if taken in sufficient quantity to raise the temperature of the feed water to such degree as will effect any substantial economy, the action of the exhaust jet upon the fire is subject to be so far diminished as to impair the steaming qualities of the locomotive. Feed water heaters designed to utilize the waste gases, have, in most, if not in all cases, been located in the smoke box, with the results of objectionably obstructing it, and of being so rapidly deteriorated by the high heat to which they are subjected, that their maintenance charges have been found to more than negative any operative economy that they might otherwise possess. Finally, while the serial application of exhaust steam and waste gases may eliminate the objection above stated to the former, that which obtains as to the latter, remains, and apparatus of this character heretofore proposed has generally been open to the further objection of complication and high structural and maintenance cost.

The object of my invention is to provide a locomotive feed water heater, which shall be of comparatively simple and inexpensive construction, and ready applicability to locomotives of any of the present standard types, in the operation of which the

coincident action, in a single structure, of portions of the exhaust steam and of the waste gases will be exerted to raise the temperature of the feed water to such degree as will effect substantial economy, without involving the exposure of any fluid resisting joints to the deteriorating action of the high heat in the smoke box.

The improvement claimed is hereinafter fully set forth.

In the accompanying drawings: Figure 1 is a side view, partly in section, of the forward portion of a locomotive boiler, illustrating an application of my invention; Fig. 2, a vertical longitudinal central section through the same; Fig. 3, a vertical transverse section, on an enlarged scale, on the line 3, 3, of Fig. 2, and Figs. 4 and 5, transverse sections on a further enlarged scale, on the lines 4, 4, and 5, 5, respectively, of Fig. 3.

My invention is herein exemplified as applied in a locomotive boiler, 4, which is of the usual construction, and is provided, at its forward end, with a smoke box, 4^a, which is supported on the ordinary cylinder saddles, 12^a. A plurality of fire tubes, 67, extends from a firebox at the rear end of the boiler, which is not shown, to the front flue sheet, 4^b, and the products of combustion pass through the tubes, in the usual manner, to the smoke box, 4^a, from which they are discharged into the atmosphere through the stack, 4^c. The usual deflecting plate or diaphragm, 4^d, extends across the smoke box, between the flue sheet and the stack, and a horizontal table plate, 4^e, which is connected to its lower end, surrounds the exhaust pipe, 64, and extends forwardly therefrom, an inclined sheet of netting or perforated plate, 4^f, being connected to its front side and extending across the smoke box.

In the practice of my invention, referring descriptively to the specific embodiment thereof which is herein illustrated, I provide a heater casing, 5, which is located on the exterior of the boiler and may be most conveniently disposed, as shown, in

front of the cylinder saddles, extending transversely thereto, and below the forward portion of the smoke box, to which it is secured, and with the curvature of which, 5 its top substantially conforms. A vertical partition or baffle plate, 5^a, extends from one end wall of the casing 5, to the other, and from its top wall to a level adjacent to that of the heater tubes to be presently 10 described. A conical draft pipe, 65^a, is fitted on the table plate, 4^a, around the exhaust nozzle, 65, the upper opening of said pipe being of such diameter as to approximate that of the jet from the exhaust nozzle, at the level of said opening. A discharge channel, 6, leads from the heater casing, 5, on one side of the partition, 5^a, to the bottom of the draft pipe, 65^a, and two waste gas suction channels, 7, the openings of which are covered by sheets of netting, 7^a, to prevent the entrance of cinders, lead from the interior of the smoke box into the heater casing, 5, on the side of the partition, 5^a, farther from the discharge channel. A cinder discharge hopper, 8, having a suitable door, 8^a, is fitted in the bottom of the heater casing.

An exhaust steam supply casing, 5^b, is formed integral with, and projects outwardly from, one of the end walls of the heater casing 5, and a substantially similar exhaust steam discharge casing, 5^c, is formed on, and projects outwardly from, the opposite end wall. The outer ends of the supply and discharge casings are closed by removable heads, 5^d, and each of said casings is divided, by a transverse partition, 5^e, into an outer compartment, 5^f, and a plurality of inner compartments, 5^g. An exhaust steam supply pipe, 9, leads from the exhaust passage, 14, of one of the cylinder saddles, into the outer compartment of the supply casing, 5^b, and an exhaust steam discharge pipe, 10, leads from the outer compartment of the discharge casing, 5^c, to any convenient and preferred point of discharge.

Each of the chambers, 5^g, of the supply casing, 5^b, is connected with one of the chambers, 5^g, of the delivery casing, 5^c, by one or more waste gas heater pipes, 11, which extend through the heater casing, 5, and are expanded, at their ends, into the end walls thereof, their outer surfaces being exposed, throughout their length, to the heat of the waste gases which pass into and out of the casing, 5. An exhaust steam heater pipe, 12, of smaller diameter, passes through each of the waste gas heater pipes, 11, and is expanded, at its ends, into plugs, 13, secured 60 in the partitions, 5^e, of the casings, 5^b, and 5^c. Feed water is supplied by an injector or pump, to one of the upper chambers, 5^g, of the casing 5^b, through a supply pipe, 15, and after passing in alternately opposite directions,

through the thin annular spaces between the 69 pipes, 11 and 12, in which spaces it is exposed, exteriorly, to the heat of the waste gases, and, interiorly, to the heat of the exhaust steam, is delivered, through a delivery pipe, 16, to a check valve on the boiler, in the ordinary manner. In its traverse through the heater, the feed water passes in alternately opposite directions through the several annular spaces between the pipes, 11 and 12, to effect which alternately opposite traverse, openings, 5^h, alternated in position relatively to the chambers, 5^g, of the casings, 5^b, and 5^c, respectively, are formed in the horizontal partitions between said chambers, as shown in Figs. 4 and 5.

In the operation of a locomotive feed water heater embodying the features of structure above described, a portion of the waste gases of combustion is, by the action of the exhaust jet, drawn into the interior of the main casing, 5, in which its heating action is exerted upon the outer surfaces of the pipes, 11, and, through the thin walls thereof, upon the columns of feed water passing through the annular spaces between said pipes and the inner pipes, 12, the current of waste gases being caused to pass, first downwardly and then upwardly, around all the pipes, 11, by the baffle plate, 5^a, after which the waste gases so utilized are discharged to and through the stack. Coincidently with this application of heat to the outer surfaces of the pipes, 11, the columns of feed water are subjected to the additional heating effect of the currents of exhaust steam which pass through the inner pipes, 12, and act, through the thin walls thereof, on the surrounding columns of feed water.

It will be apparent to those familiar with the construction and operation of locomotives, that a feed water heater embodying the essential structural and operative features of my invention, is applicable to locomotives of the various present standard designs, without interference with, or modification of, other members of the design, and also that it presents the substantial practical advantages of providing a large amount of heating surface within a comparatively small compass; of having all its steam and water joints readily accessible for repair or renewal and, particularly, of rendering available the utilization of the heat of the waste gases, without subjecting any of the steam or water joints of the appliance to the destructive action of the heat of the smoke box.

I claim as my invention and desire to secure by Letters Patent:

1. The combination, with a locomotive boiler, of a heater casing, located exterior to, and below, the boiler and its accessories; means for passing feed water through said casing; means for diverting a portion of the

- waste gases from direct passage to the stack, through the heater casing; and means for effecting the application of the heat of such diverted gases to the feed water, in its traverse through the heater casing.
2. The combination, with a locomotive boiler, of a heater casing located exterior to, and below, the boiler and its accessories; means for passing feed water through said casing; means for diverting a portion of the waste gases from direct passage to the stack, through the heater casing; and means for effecting the coincident application of the heat of such diverted gases, and of a plurality of currents of exhaust steam, to the feed water, in its traverse through the heater casing.
3. The combination, with a locomotive boiler, of a heater casing, located exterior to, and below, the boiler and its accessories; means for passing feed water through said casing; and means, operative by the exhaust jet, for diverting a portion of the waste gases from direct passage to the stack; and into and through the heater casing, thereby effecting the application of the heat of such diverted gases to the feed water, in its traverse through said casing.
4. The combination, with a locomotive boiler, of a heater casing, located exterior to, and below, the boiler and its accessories; means for passing feed water, in a plurality of annular columns, through said casing; means for diverting a portion of the waste gases from direct passage to the stack; and means for effecting the coincident application of the heat of such diverted gases, and of a plurality of currents of exhaust steam, to the outer and the inner surfaces, respectively, of the annular columns of feed water, in their traverse through the heater casing.
5. The combination, with a locomotive boiler, of a heater casing, located exterior to, and below, the boiler and its accessories; a plurality of pairs of inner and outer pipes therein; means for passing feed water through the annular spaces between the inner and outer pipes; means for passing exhaust steam through the inner pipes; and means for diverting a portion of the waste gases from direct passage to the stack, and into and through the space within the heater casing surrounding the outer pipes.
6. The combination, with a locomotive boiler, of a heater casing, located exterior to, and below, the boiler and its accessories; a plurality of pipes extending through said casing; means for passing feed water through said pipes; means, operative by the exhaust jet, for diverting a portion of the waste gases from direct passage to the stack, into the heater casing; and means for effecting the successive downward and upward movement of such diverted gases between their supply to and discharge from the heater casing.
7. The combination, with a locomotive boiler, of a feed heater casing, located exterior to the boiler and its accessories; a plurality of pipes extending through said casing; means for passing feed water through said pipes; suction channels leading from the smoke box into the casing; a conical draft pipe surrounding the exhaust nozzle; and a discharge channel leading from the heater casing to the draft pipe.
8. The combination, with a locomotive boiler, of a feed heater casing, located exterior to the boiler and its accessories; a plurality of pipes extending through said casing; means for passing feed water through said pipes; a baffle plate extending through said casing substantially to the level of the lowest of said pipes; suction channels leading from the smoke box into the casing, on one side of said baffle plate; a conical draft pipe surrounding the exhaust nozzle; and a discharge channel leading from the heater casing, on the side of the baffle plate farther from the suction channels, to the draft pipe.
9. The combination, with a locomotive boiler, of a feed heater casing, located exterior to the boiler and its accessories; exhaust steam supply and discharge casings at opposite ends thereof; each divided into an outer compartment and a plurality of inner compartments; waste gas heater pipes extending through the heater casing, each connecting one of the inner compartments of the supply casing with one of the inner compartments of the delivery casing; exhaust steam heater pipes extending through the waste gas heater pipes, from the outer compartment of the supply casing to that of the delivery casing; an exhaust steam supply pipe leading into the outer compartment of the supply casing; an exhaust steam discharge pipe leading out of the outer compartment of the discharge casing; means for passing feed water through the annular spaces between the waste gas heater pipes and the exhaust steam heater pipes; and means, operative by the exhaust jet, for traversing waste gases into and through the heater casing, around the waste gas heater pipes therein.
10. The combination, with a locomotive boiler; of a heater casing adapted to be supported exterior to the boiler, and comprising a main body portion; supply and delivery casings at the ends thereof; partitions dividing each of said casings into an outer compartment and a plurality of inner compartments; removable heads closing the outer compartments; openings establishing communication between different members of the inner compartments; a plurality of

5 pipes secured at their ends in the end walls of the main body of the casing; plugs fixed in the partitions; a plurality of pipes, of smaller diameter, secured in said plugs and passing through the first specified pipe; means for traversing waste gases from the boiler around the first specified pipes; and

means for passing exhaust steam through the smaller diameter pipes.
